UNITED STATES PATENT OFFICE.

SUMTER B. BATTEY, OF NEW YORK, N. Y.

LIQUID SELF-IGNITING DEVICE.

987,104.

Specification of Letters Patent. Patented Mar. 21, 1911.

Original application filed April 7, 1909, Serial No. 488,538. Divided and this application filed June 19, 1909. Serial No. 503,085.

To all whom it may concern:

Be it known that I, SUMTER B. BATTEY, a citizen of the United States, and a resident of the borough of Manhattan, county, city, and State of New York, have invented certain new and useful Improvements in Liquid Self-Igniting Devices, as set forth in the following specification.

This invention relates to self-igniters, and 10 is particularly applicable to self-igniting pocket lighters relying upon a catalytic agent for self-ignition and employing a vaporizable combustible liquid, such as alcohol.

It is an object of the invention to produce 15 a self-ignited flame by means of a portable, cheap and efficient device which may be manually operated with convenience and despatch.

According to the invention means is provided 20 for forcing a combustible liquid positively through a duct or conduit into the interior of a burner casing, which casing incloses the catalytic agent.

An important feature of this invention is 25 the improvement of this means, to which end there is provided a metallic receptacle forming a complete inclosure for the combustible liquid and having one or more self restoring compressible portions on its walls or 30 in its walls which may be manually depressed to force liquid through the duct or conduit into the casing.

Further objects of the invention are to 35 improve in general the construction of self-igniters and will be clear from the following description and claims which should be read in connection with the accompanying drawings forming part of this application. My prior application, Serial No. 488,538, filed 0 April 7, 1909 now Patent No. 970,294, September 18, 1910, also discloses a pocket lighter in which combustible liquid still in liquid form is introduced directly into a wickless burner casing inclosing a catalytic 5 agent.

In the accompanying drawings,—Figure 1 is a vertical section through one embodiment of the apparatus; Fig. 2 is a horizontal section through line II—II of Fig. 1; Fig. 3 is 0 a fragmentary section corresponding to Fig. 1 but showing a modification; Fig. 4 is a detail elevation; and Fig. 5 is another fragmentary elevation showing a modification.

In the embodiment illustrated, a substan-

tially flat rectangular receptacle 1 may be 55 formed of sheet metal, although the shape and material may be varied, as desired. This receptacle provides a completely enclosed chamber 2 which may be entirely filled with alcohol by removing the screw 60 threaded closure 3 and inverting the apparatus, it being borne in mind that the closure 3 should be seated to close the filling opening in the receptacle 1 before operating the lighter. In the embodiment shown the opposite walls 4 and 5 are shown provided with outwardly bulging resilient sheet metal portions 6 and 7, it being understood that these portions may be the walls themselves or inserts. Manual squeezing pressure is effective 65 in depressing both the portions 6 and 7 to decrease the cubic contents or space within the receptacle 1. The expression "depressing" is used relatively and means as here used, making an inward depression 70 from normal contour toward the interior of the receptacle 1. The portions 6 and 7 are self-restoring which means that they will spring back through their own resiliency, or through the medium of any suitable spring 75 means, to their normal positions restoring the space within the receptacle 1 to its normal extent.

A metal burner casing 8, which may be cylindrical and closed at its bottom end 9, is 80 suitably mounted relatively to the receptacle 1 and, in the embodiment shown, it is mounted parallel to but slightly spaced apart from the edge of the receptacle 1 by means of the stud 10 which may be brazed, 85 soldered, riveted, or otherwise suitably connected, as by spinning, both to the receptacle 1 and to the burner casing 8.

In the embodiment shown in Figs. 1, 2 and 3 a duct or conduit 11 is provided extending from the interior of the receptacle 1 into the interior of the burner casing 8 and emptying into a pocket like portion 12, the direction of the duct or conduit in this embodiment being transverse to the axis of the 100 casing 8. This duct or conduit is normally open as shown and when not in use liquid such as alcohol is retained within the chamber 2 by means of atmospheric pressure. The walls of the burner casing 8 provide a 105 wickless burner having a burner opening 13 which may be closed to extinguish an established flame or for other purposes by

means of a sliding sleeve 14 inclosing the cylindrical burner casing 8, to which it may be held in any suitable manner, as by friction. The top end of the burner casing is 5 shown open and provided with a removable plug 15 in which is mounted a frame 16 upon which is suspended by means of platinum filaments 17 a catalytic agent 18 in the form of a pellet and which may be sponge 10 platinum or any suitable substance. This pellet is so positioned and arranged as to be inclosed by the casing 8 and be protected against injury by the same while at the same 15 time being in proper position to effect ignition in a well known manner.

In Fig. 3 the apparatus is shown provided with additional features. An opening 19 in alinement with the duct or conduit 11 is provided in the casing 8 and may have screw 20 threaded or other engagement with an operable member shown in the form of a screw 20 manually operable and provided at its inner end with a needle 21, which may be forced through the duct or conduit 11 to 25 clean the same while the conical end 22 of the screw 20 may be forced against the bevelled mouth 23 of the duct or conduit 11 or the shank of the needle 21 may be forced in to close the conduit 11, in either case to 30 make a positive temporary closure should the same be desired as, for instance, in traveling or when the pocket lighter is not to be used for some time and when the burner opening is closed.

35 In Fig. 4, 24 indicates a screw which may be substituted for the member 20 to close the opening 19 in the burner casing if the member 20 has been removed, as it may be if desired.

40 In Fig. 5 further modifications are shown. The duct or conduit 11 previously described is present in this embodiment and in addition a second duct 25, which extends in a different direction from the duct or conduit 45 11 and may be effective in directing liquid longitudinally of the burner casing. Both ducts communicate with the interior of the receptacle 1. In this embodiment a screen or partition of wire gauze 26 is indicated 50 which may be secured in any suitable manner within the casing 8 to prevent injected liquid spattering out through the opening 13.

55 Operation: After the receptacle 1 is filled with alcohol the device may be tipped into the position shown in Fig. 1 or with the duct or conduit 11 lower and pressure applied to the portions 6 and 7 and a suitable quantity of liquid alcohol squirted out into the pocket 12. The lighter is then turned to a position 60 with the burner opening 13 uppermost and shaken or waved back and forth through the air. This shaking motion quickly effects the vaporization of alcohol within the burner casing. The vapor is ignited by the catalytic 65 agent and a flame, which will be sustained

for an appreciable time, is produced at the mouth of the opening 13. If desired, this flame may be continued indefinitely by squirting out additional charges of alcohol in a similar manner to the first operation. 70 As soon as pressure is removed from the depressible side portions 6 and 7, their resilience restores them to normal condition and sucks back into the chamber 2 more or less of the surplus alcohol in the retention pocket 75 12 at the bottom of the burner casing 8, if the alcohol covers the mouth of the duct or conduit 11.

Although it is by no means absolutely necessary for some purposes, it may be desirable 80 to have the screen to aid in preventing the spilling of the charge of alcohol during the initial shaking operation.

The flame may be extinguished by slipping the shield 14 over the burner opening 85 13 or it will go out as soon as the charge within the casing 8 has been consumed.

In carrying the device it may be well to maintain the duct 11 uppermost although 90 this is not absolutely necessary.

Although emphasis has been laid upon the injection of combustible liquid into the burner casing it is appreciated that the apparatus may be operated so as to inject not liquid but a combustible vapor. Claim is 95 therefore made for the structure for delivering combustible fluid, which term fluid includes both liquid and a gas or vapor.

To operate the device to cause the receptacle 1 to deliver a vapor through the duct 100 or conduit 11 the device should be held so that the liquid in chamber 2 does not cover or quite cover the opening into duct 11. Then, by manipulating the self restoring depressible portions 6 and 7 in and out, first, 105 vapor is delivered into casing 8, then, air is drawn back through the duct or conduit 11 and becomes charged with combustible vapor in chamber 2, and is again forced out into the burner casing. This may be kept up 110 indefinitely. It has been found that the device will accomplish self-ignition in this manner.

Although there has been illustrated and described a satisfactory embodiment of the 115 invention, it is to be understood that the same is susceptible of many satisfactory embodiments, within the scope of the accompanying claims.

What is claimed and what is desired to be 120 secured by United States Letters Patent is:—

1. In a self-igniter, a liquid receptacle forming a complete inclosure and having one or more portions of its walls depressible to decrease the space within said receptacle; 125 a burner casing inclosing a catalytic agent and providing a liquid retention pocket and a wickless burner; and a conduit leading from said fluid receptacle to the interior of 130 said burner casing and arranged to convey

said liquid from said receptacle into the retention pocket when the igniter is held in operable position and upon the depression of the said depressible portion of the receptacle.

- 5 2. In a self-igniter, a receptacle for vaporizable combustible liquid forming a complete inclosure and having a portion of its walls self-restoring and manually depressible to decrease the space within said receptacle; a burner casing inclosing a catalytic agent and providing a liquid retention pocket; said burner casing having a burner opening and providing a wickless burner; a conduit leading from said receptacle to the interior of said casing and arranged to convey said liquid from said receptacle into the retention pocket when the igniter is held in operable position and upon the depression of the said depressible portion of the receptacle.
- 10 3. In a self-igniter, a receptacle for vaporizable combustible liquid forming a complete inclosure and having a portion of its walls manually depressible to decrease the space within said receptacle; a burner casing inclosing a catalytic agent and providing a liquid retention pocket; said burner casing having a burner opening; a conduit leading from said receptacle to the interior of said casing and arranged to convey said liquid from said receptacle into the retention pocket when the igniter is held in operable position and upon the depression of the said depressible portion of the receptacle; and a wire gauze partition for said casing
- 15 30 to prevent the escape of liquid from within the said burner casing.

4. In a self-igniter, a substantially flat sheet metal receptacle forming a complete inclosure for vaporizable combustible liquid and having opposite walls depressible to decrease the space within said receptacle; a burner casing inclosing a catalytic agent and providing a liquid retention pocket and a wickless burner; and a conduit leading from said fluid receptacle to the interior of said burner casing and arranged to convey said liquid from said receptacle into the retention pocket when the igniter is held in operable position and upon the depression of the said depressible portion of the receptacle.

5. In a self-igniter, a receptacle for vaporizable combustible liquid forming a complete inclosure and having a portion of its walls manually depressible to decrease the space within said receptacle and a normally closed opening for the purpose of filling said receptacle; a burner casing inclosing a catalytic agent and providing a liquid retention pocket; said burner casing having a burner opening and providing a wickless burner; and a conduit leading from said receptacle to the interior of said casing and arranged to convey said liquid from said receptacle into the retention pocket when the

igniter is held in operable position and upon the depression of the said depressible portion of the receptacle.

6. In a self-igniter, a receptacle for vaporizable combustible liquid forming a complete inclosure and having a portion of its walls manually depressible to decrease the space within said receptacle; a burner casing inclosing a catalytic agent and providing a liquid retention pocket; said burner casing having a burner opening and providing a wickless burner; a conduit leading from said receptacle to the interior of said casing and arranged to convey said liquid from said receptacle into the retention pocket when the igniter is held in operable position and upon the depression of the said depressible portion of the receptacle; and a member providing a cleaning needle and temporary closure for said conduit.

7. In a self-igniter, a receptacle for vaporizable combustible liquid forming a complete inclosure and having a portion of its walls manually depressible to decrease the space within said receptacle; a burner casing inclosing a catalytic agent and providing a liquid retention pocket; said burner casing having a burner opening and providing a wickless burner; a conduit leading from said receptacle to the interior of said casing and arranged to convey said liquid from said receptacle into the retention pocket when the igniter is held in operable position and upon the depression of the said depressible portion of the receptacle; and a member providing a temporary closure for said conduit.

8. In a self-igniter, a substantially flat sheet metal receptacle forming a complete inclosure for vaporizable combustible liquid and having self-restoring opposite walls depressible to decrease the space within said receptacle; a burner casing inclosing a catalytic agent and providing a liquid retention pocket and a wickless burner; and a conduit leading from said fluid receptacle to the interior of said burner casing and arranged to convey said liquid from said receptacle into the retention pocket when the igniter is held in operable position and upon the depression of the said depressible portion of the receptacle.

9. In a self-igniter, in combination, a wickless burner; a catalytic agent fixed in igniting relation to said burner; and means for storing and delivering combustible fluid to said burner, comprising a metallic receptacle integral in construction forming a complete inclosure and having a depressible wall and an attenuated delivery conduit leading from the interior of said receptacle to the interior of said burner.

10. In a self-igniter, in combination, a wickless burner; a catalytic agent fixed in igniting relation to said burner; and a receptacle for containing vaporizable combus-

tible liquid and having a conduit leading from the interior of said receptacle to the interior of said burner and a self restoring integral compressible portion for forcing fluid through said conduit into the interior of said burner.

11. In combination in a pocket lighter, a burner casing providing a liquid retention pocket; a receptacle for combustible liquid; a conduit leading from the interior of said receptacle to and opening into the interior of said retention pocket; and said receptacle having a compressible, automatically restor-

able wall to force said liquid into said retention pocket upon depression and to suck back liquid from said retention pocket upon the restoration of said compressible wall to normal.

In testimony whereof, I have signed my name to this specification, in the presence of two subscribing witnesses.

S. B. BATTEY.
